UNITED STATES PATENT OFFICE.

CHARLES W. ROGERS, OF LIBERAL, KANSAS.

HYDROCARBON-BURNER.

1,283,915.

Specification of Letters Patent.

Patented Nov. 5, 1918.

Application filed November 16, 1916. Serial No. 131,746.

To all whom it may concern:

Be it known that I, CHARLES W. ROGERS, a citizen of the United States, residing at Liberal, in the county of Seward and State of Kansas, have invented certain new and useful Improvements in Hydrocarbon-Burners, of which the following is a specification.

This invention relates to an improvement in hydrocarbon burners and more particularly to burners of the type intended for use in connection with crude oil or heavy distillates, although it will be understood that the same structure might be employed in the use of lighter oil or light distillates.

An object of my invention is to provide a burner having a vaporizing cup or plate so formed that the size of the flame can be controlled by regulation of the oil supply and thus the heat given out by the burner can be accurately regulated through several predetermined degrees.

A further object lies in so constructing the vaporizing cup or plate that in its general outline it partakes of a conical form with a cup at the apex, and substantially circular or ring shaped cups formed around this cup at various heights or levels on the sloping side of the conical form of the vaporizing plate, thus providing a vaporizing cup structure which presents the central cup and the ring shaped cup in such relation that the volatile oil is fed to the cup and if a sufficient volume is not supplied to flow over the rim edge of this cup, vaporization will take place only from the one cup and as the surface area from which the gas rises is limited only a small amount of gas will be generated, whereas if the volatile oil is supplied in sufficient volume to flow over the rim edge of the central cup into the ring shaped cup the superficial area of the volume of liquid is not only increased, but the volatile liquid flowing down over the substantially vertical wall after passing over the rims of the various cups will be readily vaporized and thus the gas generation will be considerably augmented. This formation of the vaporizing cone in the conical form further so liberates the gas upon volatilization of the oil that the burning gas is spread more throughout the area of the fire pot of the stove or furnace in which the burner is being used and a better combustion occurs through more ready in-

termingling of the fresh air supply with the gas as generated.

Yet another object lies in so constructing the vaporizing cone that it can be placed in use with other burner parts especially constructed therefor or can be fitted to various types of burner structures as now already installed and in use.

With the above and other objects in view, my invention consists of certain novel features of construction and combinations of parts which will be hereinafter set forth in connection with the drawings and then more particularly pointed out in the claim.

In the drawings:

Figure 1 is a view in vertical section showing one form which the burner might take.

Fig. 2 is a transverse sectional view taken on the line 2—2 of Fig. 1.

The burner structure is intended to be installed in the fire box of a stove, furnace, or the like, and it will consequently be understood that changes and variations in the form and arrangement of the parts will necessarily be made for different adaptations. In the present disclosure I have illustrated the device in the form which it might take when built into a heating or cooking stove of the usual wood or coal burning type, and here a base plate 1 is shaped to have the rim edge 2 and has the central portion thereof raised as indicated at 3. An air supply duct 4 is located at one side of the base plate 1 and is curved at its upper end as shown at 5 to overhang the raised central portion 3 of the base plate and to have an air discharge mouth opening 6 discharging air downwardly toward this raised central portion. The air supply passage 4 may be cast or formed integral with the base plate 1 or may be made separate as is shown in the present illustration, and the air discharge opening 6 is preferably elevated somewhat above the raised portion 3 of the plate 1. An oil supply pipe 7 is led up through the air passage 4 and has its discharge end 8 centrally disposed over the base plate 1, a valve 9 being connected in this supply pipe 7 to control and regulate the flow of oil therethrough. In installing the structure as described, the base plate will be fitted in the fire pot of the usual form of stove or a special stove might be provided and in either case this base plate is mounted to have an air tight connection around its edge, the air

passage 4 however being left open. The supply pipe 7 will be extended to a suitable source of oil supply and the valve 9 will be located at any convenient point, it of course being understood that it is preferable that some means be arranged to control the passage of air through the duct or passage 4. All of the parts as described are of substantially standard form and might be varied practically without limitation to bring the device to fit the particular use to which it is to be put, this part of the structure being flexible even to the extent that the raised portion 3 of the base plate might be dispensed with and the air supply passage might be arranged to be entirely independent of the base plate, although it is perhaps desirable that the air passage be disposed somewhat after the manner shown as the heating of the air in its passage to the burner not only causes better circulation but also causes the hydro-carbon oil to be more readily volatilized.

A vaporizing cone which is generally indicated by the numeral 10 is made to be substantially conical in its general outline, and at its apex this member 10 has an oil recess 11. The member 10 is shaped on its bottom portion to fit substantially over the top of the raised portion 3 and it is perhaps desirable that these parts be mated so that the vaporizing cone will be held at all times in a predetermined relation where the recess 11 is immediately beneath the discharge end 8 of the oil supply pipe 7 and is consequently centralized beneath the air discharge opening 6 of the passage 4. The oil grooves 12, 13, and 14, which in the present disclosure are made of substantially ring shape and are disposed concentrically around the recess 11 are formed in stepped relation so that each takes a lower level than the recess next in size, and thus as oil is supplied into the recess or cup 11, in a sufficient quantity to flow over the top rim edge thereof, this oil will flow down over the substantially perpendicular inside wall of the next adjacent ring like recess or cup and the flow will be from the one ring like recess or cup to the other, of course depending upon the rate of flow of the oil and the volatility thereof. Where only a small quantity of oil is supplied through the pipe 7, the volatilization of this oil will be at such a rate that there will not be any flow over the rim of the recess 11 into the next adjacent recess or cup 12 and consequently the surface from which the volatilization of the oil occurs will be comparatively small in its area. This relatively small area of oil will give off a correspondingly small volume of combustible gas and thus the flame supplied by this volume of gas will be of small size however, immediately the supply of oil is increased to such an extent that

there is an overflow from the recess or cup 11 to the concentric cup or recess 12, the heated outer surface of the substantially perpendicular inner wall of the recess 12 will gassify a certain part of the oil passing thereover and the excess oil flowing into the recess or cup 12 will increase the area from which gas is rising due to the volatilization of the oil through the heated surrounding air, and consequently the flame volume is considerably increased and intensified. This action will of course be understood to be increased as the flow of oil is increased to create overflow from one cup to another and thus it will be seen that in the form of device as shown in the present illustration, by manipulation of the valve 9 the supply of oil can be controlled to such an extent that four various degrees of burner flame and consequently four regulations of heat can be made, and even then other variations are obtainable intermediate the main steps or divisions of rise or fall.

While in the illustrations I have shown only one form of the vaporizing cone, namely the form in which the member 10 is made of substantially conical configuration with a central orifice or cup 11 and the ring shaped cups or recesses 12, 13, and 14 arranged concentrically therearound, it will be appreciated that in some adaptations the member 10 might partake of the form of a pyramid, might present a rectangular or elliptical base outline with the side walls raised in the gradual incline or slope to a common center or to a ridge center, and that in some adaptations the pitch or angle of the side might also be varied without limitation, the structure being such that under some circumstances it might even be found practical to make the rim edges of the several cups or recesses to lie in substantially the same plane. It will further be apparent that other changes might be resorted to in the form and arrangement of this member 10 to fit the same for various types of burners, however, as all of these forms will be used only to fit the device for various adaptations and as all are outgrowths of the structure illustrated in the drawings, it is not deemed necessary to here endeavor to make showing of all of the modifications which might be resorted to and it will be understood that the above are only some of the forms which might be taken by the vaporizing cone 10.

From the foregoing it will be seen that I have provided a vaporizing cone and a burner embodying the same in such a manner that crude oil or other heavy distillate, or light oil and light distillates can be burned with maximum efficiency, that the size of the flame is at all times within the control of the user, that the arrangement of the various oil recesses or cups one above

the other from the outer edge toward the center disposes the same in such relation that the air as supplied for the purpose of volatilizing the oil and supporting combustion will spread the flame to give the greatest heating action, and that the supply of air and the passage of the same adjacent to the vaporizing plate in the manner as set forth will give better vaporization and a better combustible mixture thus practically eliminating the formation of carbon or the giving off of smoke or gases during burning.

While only one specific form of burner and one particular design and type of vaporizing cone have been particularly illustrated, it will be evident that changes as set forth above and other variations can be resorted to in the form and arrangement of the parts, and hence I do not wish to be limited to the exact disclosure but only to such points as may be set forth in the claim.

I claim:

An oil burner comprising a base plate

having a rim edge, said base plate having 25 its central portion raised to provide an annular groove therein, for receiving oil, a vaporizing cone having a plurality of concentrically arranged ring shaped oil receiving cups formed in the sloping side wall 30 around the central oil retaining cup and provided with substantially perpendicular inside walls, said vaporizing cone being supported by said raised central portion, so that the cone will be above the level of the 35 oil in the annular groove of the base-plate, and an air supply passage detachably connected to one side of the plate, the upper end of said passage being curved to overhang the central oil retaining cup of the 40 vaporizing cone.

In testimony whereof I affix my signature in presence of two witnesses.

CHARLES W. ROGERS.
